AERATING DEVICE

Raymond T. Goodrie, Calumet City, Ill., and Joseph J. Goodrie, deceased, late of Lansing, Ill., by Ethel L. Goodrie, administratrix, Lansing, Ill., assignors to Wrightway Engineering Co., Chicago, Ill., a corporation of Illinois

Filed Oct. 27, 1959, Ser. No. 849,427

3 Claims. (Cl. 239—432)

This invention relates to improvements in aerating devices of the type adapted to be connected to water faucets and the like.

Aerating devices for mixing water and air are now widely known and used on faucets and other water outlets. Such devices are highly useful and advantageous since in their preferred form they produce a soft, bubbly, coherent stream which is non-splashing and which contains large amounts of entrained air. Various structures have been proposed for such devices, e.g. as shown in Joseph J. Goodrie Patents 2,510,395 and 2,510,396 wherein the device has a cylindrical mixing chamber provided with lateral air ports, an apertured disk for forming jets of water within the chamber, a breakup plug against which the jets impinge, and means at the outlet of the chamber for coalescing the water and entrained air.

An aerating device of the foregoing type is provided with a threaded connection or other equivalent means for detachably mounting the aerator at the open end of a faucet or other fluid supply conduit. Thus, the aerating device itself extends downwardly from the end of the faucet so as to increase the over-all length of the faucet to a greater or lesser degree dependent upon the size of the aerator. Various improved aerator designs have been proposed, e.g. as in Joseph J. Goodrie Patent No. 2,761,662, wherein the axial length of the aerating device is considerably shortened as compared with prior designs. However, even in these instances the aerator still comprises a visible appendage at the end of the faucet. From an appearance viewpoint, it would be highly advantageous to have available some form of aerating device which is substantially concealed when mounted on the end of a faucet. Furthermore, for several sanitary and health reasons, it is frequently considered desirable to avoid lengthening a faucet outlet as usually occurs when an aerating device is attached to the faucet. For example, various plumbing codes and regulations place restrictions on the over-the-rim or overflow clearance between a faucet outlet and sink in order to eliminate the possibility of back-siphoning of dirty water. Consequently, an aerator device which avoids lengthening a faucet outlet would be a considerable advantage in enabling manufacturers and contractors to comply with such regulations. In addition, the conventional aerators heretofore known have lateral air inlet ports or slots which permit discharge of liquid therethrough if the normal outlet is obstructed or plugged. Such slots also afford areas for the accumulation of dirt and debris due to repeated cleaning or polishing of the faucet and attached aerator.

Accordingly, a primary object of the present invention is to provide a novel and improved aerating device which is constructed so as to be substantially concealed when mounted on a faucet.

A further object of the invention is to provide a novel and improved aerating device having means for mounting the same internally of a faucet outlet so that there is no appreciable increase in the length of the faucet.

Another object of the invention is to provide a novel aerator construction in which the usual lateral air inlet ports have been eliminated so as to avoid the possibility

2

of liquid being discharged laterally from the aerator and also to avoid accumulation of dirt or debris at the exterior of the aerator.

Other objects and advantages of the invention will be 5 come evident from the subsequent detailed description taken in conjunction with the accompanying drawing, wherein:

FIG. 1 is a side elevational view of a faucet outlet having mounted thereon an aerator comprising one specific 10 embodiment of the invention;

FIG. 2 is an enlarged longitudinal sectional view taken along the line 2—2 of FIG. 1;

FIG. 3 is a transverse sectional view taken along the line 3—3 of FIG. 2; and

FIG. 4 is a transverse sectional view taken along the line 4—4 of FIG. 2.

Referring to the drawing, the aerating device of the present invention is mounted on the end of a fluid supply conduit or faucet shown fragmentarily at 11 and having 20 an internally threaded open end portion 12. The aerating device itself has a cylindrical or tubular casing 13 of relatively short axial length and of a diameter such as to fit within the fluid supply conduit 11. The central portion of the casing 13 is provided with external threads 14 adapted to interfit with the internally threaded end 12 of the conduit 11. The outer end of the casing 13 is formed with a radially outwardly projecting flange portion 16 which abuts the axial end surface of the conduit 11 when the casing 13 is screwed into the end of the conduit. Preferably, the outer peripheral surface of the flange portion 16 is knurled or roughened, as seen at 17 in FIG. 1, in order to facilitate installation and removal of the aerator. The inner wall of the conduit 11 above the threaded portion 12 is counter-bored, as at 18, and is 35 rigidly fitted with a short sleeve 19 having an inwardly radially projecting abutment or flange 20 for the purpose described hereinafter.

The upper end of the casing 13 is counterbored slightly to provide shoulder means upon which are supported a 40 baffle collar 21 having a depending annular skirt portion 22 and a transversely extending disk 23 provided with a multiplicity of apertures 24 which in this instance are arranged in a circle (FIG. 3). For ease of assembly and disassembly, the collar 21 and the apertured disk 23 have 45 a slightly loose fit in the upper end of the tubular casing 13 so as to be readily detachable. When the threaded casing 13 is in fully tightened position on the end of the faucet 11, a gasket 26 of rubber or the like is clamped between the disk 23 and the radial flange 20 thereby providing a fluid-tight seal so that water under pressure 50 from the faucet 11 is forced through the apertures 24 to provide a multiplicity of substantially independent or discrete jets which are surrounded by air, as hereinafter described, in an internal mixing zone 27 within the aerator.

A depending breakup or mixing plug 28 is suspended 55 centrally from the disk 23 and is so shaped that the plurality of fine jets from the openings 24 which entrain air in passing through the zone 27 impinge upon the plug and are broken up and mixed with the entrained air.

The illustrated shape of the plug 28, which is more or 60 less like that of a mushroom, has been found to give highly effective results. The plug 28 has a restricted neck portion 29 immediately below the apertured disk 23 and then an abrupt radially extending enlargement or button portion 31 which provides the primary water jet break-

65 up function of the device. The enlargement 31 has a smoothly curved shoulder or downwardly rounded corner portion 32 disposed beneath the apertures 24 so that the liquid jets may impinge thereon and be diverted in many different directions. The enlarged portion 31 of the 70 breakup plug 28 may be said to have a generally toroidal or oblate spheroidal shape.

At the lower or outlet end of the casting 13 a tubular partition 36 is mounted in concentric relation within the casing and in inwardly spaced relation from the inner wall thereof so as to provide an annular air inlet passage 37. The lower end of the plug 28 extends into the upper end portion of the tubular partition 36 which has an internal diameter greater than the diameter of the plug body 28 and is flared radially outwardly to provide a supporting flange portion 38 which is formed with a plurality of edge openings 39 (FIG. 4) so that the flange 10 has a generally scalloped appearance. An inner shoulder 41 is formed in the casing 13 for detachably supporting the flange 38. The axial length of the tubular partition 36 is such that the lower end thereof is in substantially flush alignment with the lower axial end portion 16 of the casing 13, as best seen in FIG. 2. Intermediate its ends, the tubular partition 36 is restricted slightly so that the lower or outlet end portion of the tubular partition has a smaller internal diameter than the upper end portion thereof and thereby providing an annular shoulder 20 for supporting a foraminous element or screen 42 in spaced relation below the breakup plug 28.

In operation, water under pressure enters the upper or inlet end of the casing 13 and is forced through the apertures 24 in the disk 23 thereby creating a multiplicity of fine separate jets of water below the disk 23. Because of their discrete or relatively independent nature, these jets are entirely surrounded by air which freely enters the space 27 within the casing 13 by passing upwardly through the annular passageway 37 and the openings 39. As the water jets pass downwardly through the space 27 while surrounded by air, the air becomes entrained in the jets and the latter then impinge with considerable force against the curved shoulder portion 32 of the plug 28.

The violent impingement of the water jets against the curved surface causes considerable splashing and breakup of the jets in all directions thereby further intimately mixing the water and the air. Obviously, some of the water will be thrown back against the underside of the disk 23 and some will also be thrown outwardly against the skirt 22. The splashing water may be in the form of sprays or separate droplets depending upon the degree of breakup. Furthermore, some of the water will adhere to the plug 28 as a thin film and pass downwardly along the curved outer surface of the plug to the relatively flat bottom surface thereof. In accordance with the known requirements for proper aerator operation, the annular opening, designated at 43 in FIG. 2, between the lower end of the skirt 22 and the enlarged plug portion 31 must have a greater area than the combined area of the openings 24 in the disk 23. By means of this relationship, there is no tendency for the incoming water to collect in and fill up the space 27. Consequently, proper impingement and breakup of the individual water jets and entrainment of air therein are realized because of the absence of restrictions to fluid flow downstream from the openings 24.

The mixture of commingled air and water passes downwardly through the annular space 43. It will be noted from FIG. 2 that although the skirt 22 is spaced annularly from the breakup plug 31, nevertheless, the internal diameter of the skirt 22 is substantially less than the internal diameter of the tubular partition 36, the latter being disposed in coaxial alignment with and in axially spaced relation below the skirt 22. Thus, the intimate mixture of air and water which is discharged in an annular stream through the opening 43 is directed or diverted into the relatively enlarged upper end of the tubular portion 36 by reason of the relatively smaller diameter baffle skirt 22. The aerated fluid stream is discharged downwardly through the center of the tubular partition 36, as indicated by the arrows in FIG. 2, while at the same time air may pass upwardly in countercurrent concentric relation through the annular passage 37, as also

shown by arrows in FIG. 2. As the aerated stream enters the enlarged upper end of the tubular partition 36, further rebound and impingement may occur as a result of the splash surfaces provided by the inner wall of the tubular partition 36 above the screen 42 and the cooperating opposed surfaces of the breakup plug 31. The aerated stream discharges through the screen 42 and the restricted lower end of the tubular partition 36. The screen 42, although not absolutely essential to the operation of the aerator, is desirable since it tends to coalesce the air and entrained water into a coherent stream and tends to give a somewhat "softer" flow which assists in imparting non-splashing characteristics to the stream.

From the foregoing it will be seen that when the aerating device has been threadedly mounted within the discharge end of the fluid conduit or faucet 11, the aerator is substantially concealed from view, the only visible portion being the lowermost narrow rim or flange 17, as seen in FIG. 1. Furthermore, since the major portion 15 of the axial length of the aerating device extends axially upwardly within the interior of the faucet, it will also be seen that there is no appreciable lengthening of the faucet by reason of the attachment of the aerator. Thus, the invention provides an improved appearance in devices of 20 this character while at the same time complying with good sanitary practices and health regulations. Inasmuch as the fluid conduit 11 and the aerator casing 13 are closed at their sides and have only the end openings, it will be recognized that the conventional lateral air inlet 25 ports have been entirely eliminated. Consequently, it is impossible for liquid to be discharged laterally from the faucet in case the discharge outlet is obstructed or even completely blocked off. Also, there is no opportunity for dirt or debris to accumulate.

30 Although the invention has been described with reference to a particular structural embodiment thereof, it is to be understood that various modifications and equivalent structures may be resorted to without departing from the scope of the invention as defined in the appended 35 claims.

We claim:

1. An aerating device comprising a tubular casing having a liquid inlet at one end thereof and an outlet at the other end thereof, an apertured disk extending across said 40 casing adjacent the inlet end thereof, a breakup and mixing body affixed to said disk and extending toward the outlet end of said casing and adapted to have liquid jets from said disk impinged thereon, a tubular partition mounted concentrically within said casing adjacent the 45 outlet end thereof, said tubular partition having an inner end portion of enlarged diameter spaced downstream from said disk relative to the direction of liquid flow through said casing and said tubular partition also having an outer end portion of restricted diameter terminating at the outlet end of said casing, said body extending into 50 and terminating in said enlarged diameter inner end portion of said partition, and an annular baffle within said casing spaced concentrically around said body and extending from said disk toward the outlet end of said 55 casing and terminating in an end spaced upstream from said inner end portion of said tubular partition, at least a portion of the outer periphery of said tubular partition being spaced inwardly from said casing to provide axially 60 extending air inlet means therebetween for admitting air from the outlet end of the casing into the space between the end of said baffle and the inner end portion of said partition, and said baffle having an internal diameter less than the internal diameter of said inner end portion of said tubular partition whereby an annular liquid stream is directed into said enlarged diameter inner end portion of said tubular partition and thence through said 65 restricted diameter outer end portion of said tubular partition.

2. The device of claim 1 further characterized in that

said tubular partition is formed at its inner end with a radially outwardly extending scalloped flange portion engaging the inner wall of said casing for supporting the partition in concentric relation within the casing and also permitting passage of air therethrough.

3. The combination of claim 1 further characterized by the provision of a foraminous element mounted transversely across said tubular partition at the juncture between said inner end portion and said outer end portion. 10
